CLAIM

The ornamental design for a corn shaped toy, as shown and described.

DESCRIPTION

FIG. 1 is a front perspective view of a corn shaped toy, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view showing my design. The broken lines in the drawings depict portions of a corn shaped toy that form no part of the claimed design. In the drawings, the evenly-spaced broken lines and the broken line pattern on the husks of the article depict portions of the article that form no part of the claimed design.
